ELECTRICAL CONDUCTOR

Leo L. Weaver, Cranford, and Carroll A. Webber, Westfield, N. J.; said Weaver assignor to Western Electric Company, Inc., New York, N. Y., a corporation of New York, and said Webber assignor to Bell Telephone Laboratories, Incorporated, New York, N. Y., a corporation of New York

Application January 10, 1935, Serial No. 1,104

15 Claims. (Cl. 173—367)

This invention relates to electrical conductors and more particularly to self coiling electrical conductor cords and to a method of making them.

It is desirable to have the ordinarily substantially limply flexible conductor cords used on telephone subscribers' sets made elastically retractile or self-coiling so that when not in use the cord will automatically coil itself into a compact and unobtrusive small bundle.

One object of the present invention is to provide an improved self-coiling conductor cord for use in connection with telephone sets and in analogous applications.

In one embodiment thereof, the invention contemplates a coiling element to be associated with the electrical conductor strands within a conductor cord, comprising a precoiled, elastically tempered length of spring wire, in which the ends of the wire have been flattened to form slightly protruding corners and a tightly coiled helix of spring wire having the inner diameter of the helix such as to engage the corners above mentioned in the screw thread defined between the coils of the helix, screwed over each end of the coiling spring and extending out beyond the ends. A sleeve of flexible wear resisting material such as a short length of tubular textile braid impregnated and coated with varnish is slipped over each of the terminal helices and a textile sheath braided over the whole.

Other objects and features of the invention will appear from the following detailed description of one embodiment thereof taken in connection with the accompanying drawing in which the same reference numerals are applied to identical parts in the several figures and in which

Fig. 1 is a broken view in perspective of a telephone cord constructed in accordance with the invention;

Fig. 2 is an enlarged section on the line 2—2 of Fig. 1;

Fig. 3 is an enlarged view partly in longitudinal section of one end of the coiling element of Fig. 1, and

Fig. 4 is an exploded view of one end of the coiling spring and of the tight helix to be threaded thereon.

In the embodiment of the invention herein disclosed, a suitable length of piano wire 20, or of material having similar elastic properties, is formed into a permanent elastically deformable helix, and its ends are flattened as at 21 to form corners 22 extending laterally beyond the normal contour of the wire. Another appropriate length of spring wire is formed into a tight helical coil

24 whose inner diameter approximates the diameter of the wire 20 and is less than the distance between the two corners 22, 22. This helix 24 is then put in place on the end of the wire 20, as shown best in Fig. 3, by being screwed into place thereon, the corners 22, 22 engaging in the helical trough or space between the coils of the helix 24. Such a helix 24 is preferably placed over each end of the wire 20. The outer end of each helix 24 is preferably also formed with an axially oriented loop 25.

After the helices 24, 24 are in place, textile threads or cords 26, are secured to the loops 25, and then a protective sleeve 27 is slipped over each helix 24. Each sleeve 27 may preferably be a short section of what is commercially known as "varnish tubing", i. e. a length of braided textile tubing impregnated and coated with linseed oil varnish or cellulose acetate enamel or the like. A series of elements thus prepared is connected in sequence by the cords 26 being attached at each end to a first loop 25 of one element and a last loop 25 of another forming a continuous chain of such elements. This chain is then fed through a braiding machine and a continuous braided cover 28 formed thereon.

The customary three insulated electrical conductors 30, 30, 30 for a telephone cord are then associated with the chain strand of coiling elements produced as described above and these four strands are then fed through a braiding machine together and covered together with a braided textile sheath 29. When completed, the individual cord lengths are formed by cutting the whole midway between the ends of successive coiling elements. Each cord thus made is like that shown in Fig. 1. The coiling element 20 plus its end helices 24, 24 extends continuously throughout most but not all of the length of the cord, there being at each end a portion preferably some four to eight inches long extending beyond the ends of the helices 24, these parts being relatively limp and flexible as compared with the greater central length of the cord containing the coiling spring. Hence when the two ends of the cord are secured, e. g., to the receiver and base of a telephone, the coiling element forces the greater part of the cord into a compact helix. When this helix is forced to lengthen by the receiver being removed from the base, the coil in straightening tends to twist and the relatively limp and flexible ends of the cord beyond the spring yield to and take up this twist freely, and lose it again when the helix is permitted to close again by replacing the receiver.

The helices 24, 24 prevent any sharp bending or kinking of the cord over the ends of the spring 28 and the sleeve 27 prevents the coils of the helices 24, 24 from nipping or unduly wearing the threads of the sheath 28.

The loops 25 and link threads 26 are not necessary but are convenient for continuous manufacture, as without them consecutive coil springs 20 must be fed at intervals by hand through a 10 braider to receive the sheath 28.

The entirely limp sheath 28 outside of the loops 25 may be conveniently used as tie cords to fasten the ends of the cord in place and so relieve the conductors of any longitudinal jerks and strains 15 in use.

Although herein disclosed as embodied in a telephone cord, the invention is not limited to such and this embodiment may be widely varied and departed from without departing from the 20 spirit and scope of the invention as pointed out in and limited solely by the appended claims.

What is claimed is:

1. In a self coiling element for flexible electrical conductors, an elastic coiled core strand, a sheath 26 over the core strand and flexible means on an end of the core strand within the sheath to prevent the end of the core strand from damaging the inside of the sheath.

2. In a self coiling element for electrical conductors, an elastic coiled core strand, a sheath 30 over the core strand and means to prevent an end of the core strand from damaging the inside of the core strand sheath, the means comprising a strand coiled into a helix part of which encloses 35 the end of the core strand.

3. In a self coiling element for electrical conductors, an elastic coiled core strand, a sheath over the core strand and means to prevent an end of the core strand from damaging the inside 40 of the core strand sheath, the means comprising a strand coiled into a helix part of which encloses the end of the core strand, the end of the core strand being provided with projections engaging in the helical trough between adjacent coils of 45 the helix thereon.

4. In a self coiling element for electrical conductors, an elastic coiled core strand, a sheath over the core strand and means to prevent an end of the core strand from damaging the inside 50 of the core strand sheath, the means comprising a strand coiled into a helix part of which encloses the end of the core strand and an inner sheath over the last named helix and within the first named sheath.

5. In a self coiling element for electrical conductors, an elastic coiled core strand, a sheath over the core strand and means to prevent an end of the core strand from damaging the inside 60 of the core strand sheath, the means comprising a strand coiled into a helix part of which encloses the end of the core strand and an inner sheath over the last named helix and within the first named sheath, the end of the core strand being provided with projections engaging in the helical trough between adjacent coils of the helix thereon.

6. A self coiling electrical conductor cord comprising an electrically conductive conductor strand, a coiling element having an elastic coiled core strand, a sheath over the core strand and means to prevent an end of the core strand from 70 damaging the inside of the core strand sheath, the means comprising a strand coiled into a helix part of which encloses the end of the core strand,

and an outer sheath over both the conductor strand and the coiling element.

7. A self coiling electrical conductor cord comprising an electrically conductive conductor strand, a coiling element having an elastic coiled core strand, a sheath over the core strand and means to prevent an end of the core strand from damaging the inside of the core strand sheath, the means comprising a strand coiled into a helix part of which encloses the end of the core strand, 10 the end of the core strand being provided with projections engaging in the helical trough between adjacent coils of the helix thereon, and an outer sheath over both the conductor strand and the coiling element. 15

8. A self coiling electrical conductor cord comprising an electrically conductive conductor strand, a coiling element having an elastic coiled core strand, a sheath over the core strand and means to prevent an end of the core strand from 20 damaging the inside of the core strand sheath, the means comprising a strand coiled into a helix part of which encloses the end of the core strand and an inner sheath over the last named helix 25 and within the first named sheath, and an outer sheath over both the conductor strand and the coiling element.

9. A self coiling electrical conductor cord comprising an electrically conductive conductor strand, a coiling element having an elastic coiled core strand, a sheath over the core strand and means to prevent an end of the core strand from 30 damaging the inside of the core strand sheath, the means comprising a strand coiled into a helix part of which encloses the end of the core strand 35 and an inner sheath over the last named helix and within the first named sheath, the end of the core strand being provided with projections engaging in the helical trough between adjacent coils of the helix thereon, and an outer sheath 40 over both the conductor strand and the coiling element.

10. A self coiling electrical conductor cord comprising an electrically conductive conductor strand, a coiling element having an elastic coiled core strand, a sheath over the core strand and means to prevent an end of the core strand from 45 damaging the inside of the core strand sheath, the means comprising a strand coiled into a helix part of which encloses the end of the core strand, 50 and an outer sheath over both the conductor strand and the coiling element, the conductor strand and the outer sheath extending beyond the free end of the helix on the end of the coiling element. 55

11. A self coiling electrical conductor cord comprising an electrically conductive conductor strand, a coiling element having an elastic coiled core strand, a sheath over the core strand and means to prevent an end of the core strand from 60 damaging the inside of the core strand sheath, the means comprising a strand coiled into a helix part of which encloses the end of the core strand, 65 and an outer sheath over both the conductor strand and the coiling element, the conductor strand and the outer sheath extending beyond the free end of the helix on the end of the coiling element. 70

12. A self coiling electrical conductor cord comprising an electrically conductive conductor strand, a coiling element having an elastic coiled core strand, a sheath over the core strand and 75

means to prevent an end of the core strand from
damaging the inside of the core strand sheath,
the means comprising a strand coiled into a
helix part of which encloses the end of the core
strand and an inner sheath over the last named
helix and within the first named sheath, and an
outer sheath over both the conductor strand and
the coiling element, the conductor strand and
the outer sheath extending beyond the free end
10 of the helix on the end of the coiling element.

13. A self coiling electrical conductor cord
comprising an electrically conductive conductor
strand, a coiling element having an elastic coiled
core strand, a sheath over the core strand and
15 means to prevent an end of the core strand from
damaging the inside of the core strand sheath,
the means comprising a strand coiled into a
helix part of which encloses the end of the core
strand and an inner sheath over the last named
20 helix and within the first named sheath, the
end of the core strand being provided with pro-
jections engaging in the helical trough between
adjacent coils of the helix thereon, and an
outer sheath over both the conductor strand and

the coiling element, the conductor strand and
the outer sheath extending beyond the free end
of the helix on the end of the coiling element.

14. A method of making electrical conductor
cords which includes the steps of forming a plu-
rality of permanently helically coiled elastically
deformable lengths of self coiling strands, flexi-
bly interlinking the lengths of strand, forming a
continuous textile cover over the lengths of
strand and the links therebetween, forming a 10
textile cover over the interlinked covered strands
and a flexible electrical conductor placed in par-
allel with the strands and severing the assem-
bly into separate self coiling cords.

15. An electrical conductor cord having a con-
ductive strand, a self coiling strand assembled
in parallel engagement therewith, a textile
sheath over the self coiling strand individually,
and tie-cords consisting of integral extensions
of the sheath extending beyond the ends of the 20
strand therein.
